United States Patent Office.

JONATHAN CRABTREE, OF PHILADELPHIA, PENNSYLVANIA, ASSIGNOR
TO JAMES BROMLEY & BROTHERS, OF SAME PLACE.

Design No. 3,717, dated October 19, 1869.

DESIGN FOR A CARPET-PATTERN.

The Schedule referred to in these Letters Patent and making part of the same.

I, JONATHAN CRABTREE, (assignor to the firm of JAMES BROMLEY & BROTHERS,) of Philadelphia, county of Philadelphia, State of Pennsylvania, have invented a Design for a Carpet-Pattern, of which the following is a specification.

In the drawing, sufficient of the pattern is shown to illustrate my design, the remainder of the pattern being merely a repetition of that which appears in the figure.

The main feature of the design is a broad stripe, A, composed of flowers, leaves, and stems, arranged substantially as shown in the drawing; these stripes of one portion of the pattern being at right angles to those of the other portion, so as to enclose square or diamond-shaped figures B, the interiors of which are

ornamented by dotted lines a, crossing each other at right angles, and forming squares, in each of which is a dot, c.

Irrespective of the colors employed,

I claim the design for a carpet-pattern, substantially as described, and represented in and by the accompanying drawing.

In testimony whereof, I have signed my name to this specification, in the presence of two subscribing witnesses.

JONATHAN CRABTREE.
